MICROMETRIC COMPASS

William Dankhoff, deceased, late of Falls Creek,
Pa., by Laurel C. Frey, administrator, Grafton,
W. Va.

Application March 13, 1934, Serial No. 715,369

5 Claims. (Cl. 33—154)

This invention relates to an improved micrometric instrument and has more particular reference to a novel measuring and adjusting gauge for such instruments as calipers, dividers and compasses.

The invention as depicted in the accompanying drawings comprises a gauge equipped compass, it being understood that the same fundamental structural arrangement is susceptible for use in the construction of an equivalent instrument, such as a caliper, divider and the like.

Where accuracy and precision is required in tools and instruments of this classification, dependable and efficient means must be provided for moving the legs of the instrument toward and from each other in a minute manner, and at the same time to definitely and legibly indicate the distance between the points of said legs. The inventor of the invention herein having discovered the need for an arrangement of this type, evolved and produced a unique structural assemblage characterized by features carefully selected and mechanically co-ordinated to accomplish the desired results in a practicable and satisfactory manner.

The preferred embodiment of the invention will become more readily apparent from the following description and drawings.

In the drawings:—

30 Figure 1 is an elevational view of a pair of dividers in which the improvement is incorporated.

Figure 2 is an elevational view observing Figure 1 in the direction from left to right.

35 Figure 3 is a sectional view taken approximately on the plane of the line 3—3 of Figure 2.

Figure 4 is a detail horizontal sectional and elevational view taken approximately on the plane of the line 4—4 of Figure 1.

40 Figure 5 is a perspective view of a self-adjusting anchoring and supporting ring or annulus.

Figure 6 is a detail elevational view of the feed-nut.

45 In the drawings, in Figure 1 for example, it will be observed that the instrument, known as a pair of dividers, is distinguished by the numeral 1. This is of more or less conventional form in that it embodies a pair of legs 8 and 9 pivotally connected together at their upper or converging ends, as indicated at 10. At opposed points and adjacent the pivot, the legs are formed with ring-like enlargements 11 and 12 adapted for registration and designed to accommodate the adjusting, 50 measuring and indicating means. This means is

composed of a number of carefully selected and mechanically co-ordinated parts.

Attention is first called to the numeral 13 which designates a hollow cylindrical adjusting and measuring screw. This is merely formed with a spiral groove 14 and provided at one end with a fixed, knurled head or finger grip 15. The opposite end is internally screw threaded, as indicated in Figure 3, to accommodate the threaded stem or shank 16 of a detachable, knurled cap 17. 5 Adjacent the cap, the adjusting screw is fashioned for swivel mounting in a self-adjusting oscillatory annulus or ring 18. This ring is made to fit swingably in the supporting annulus 12. To this end, said annulus 12 is provided at diametrically opposite points with bearing holes to accommodate diametrically opposed trunnions or pintles 19 carried by said ring. The right hand end of the feed screw is mounted for swivelling in this ring 18 and the ring is in turn mounted 10 for oscillation in the annulus 12. The cap 17 is removable to permit the parts to be assembled and disassembled. Incidentally, the feed screw is made hollow to render it light in weight. Moreover, the threads, that is, the portions between 15 the grooves, are provided with calibrations or graduations 20 which serve in a manner to be hereinafter described.

Attention is called at this time to the numeral 21 which designates what may be conveniently 30 described as a feed nut. This is provided with diametrically opposite trunnions 22 mounted for oscillation in bearing holes formed in the annulus 11. Moreover, the nut is fashioned or threaded 35 for adjusting cooperation with the groove 14 of the feed screw, as detailed in Figure 4. Then too, it is provided with a pointer or index 23 for cooperation with the graduations or calibrations 20, as shown in the assembled view in Figure 1.

The gist of the invention is in the provision of a double legged instrument 7 wherein the legs are pivotally attached at one end and provided intermediate their ends with opposed annular enlargements. The enlargement 12 serves to accommodate a self-leveling or adjusting ring 18 45 which is mounted for swivelling therein. The enlargement 11 serves to accommodate a correspondingly mounted or swingable feed nut carrying an index or pointer 23. This permits one end portion of the feed screw 13 to be swivelly mounted in the ring 18, the intermediate or opposite end portion of said screw extending adjustably through said nut 21. Thus in a sense, we have a calibrated adjusting screw which serves as a gauge 50 and which is operatively connected with the legs 55

8 and 9 to adjust said legs toward and from each other in a desired manner. Through the instrumentality of the pointer 23 cooperating with the graduations 20, it is thus possible to determine the distance between the pointed ends of said legs 8 and 9.

An arrangement of this type is adaptable, as before indicated, to different types of instruments, such as dividers, compasses, calipers and the like. It is, in a sense, an adjusting and indicating micrometer. It makes for accurate and dependable adjustment and measurement. In contrast to known types of instruments, it appears to be a unique adaptation whose features of construction transcend those of similar arrangements.

It is thought that the description, taken in connection with the drawings, will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

It is claimed:

1. A structure of the class described comprising an instrument embodying a pair of legs one of which is adjustable toward and from the other, a feed nut carried by one of said legs, an adjusting screw operatively connected with said feed nut, a swivel connection between one end of said screw and the remaining leg, said nut being provided with an indicating pointer, and said feed screw being provided with graduations with which said pointer is co-operable.

2. A device of the class described comprising an instrument including a pair of legs one of which is adjustable toward and from the other, an anchoring ring pivotally mounted on one of said legs, a feed nut pivotally mounted on the opposite leg in alignment with said ring, a feed screw adjustably connected with said nut and

swivelly connected with said ring, said nut being provided with an indicating pointer, and said feed screw being provided with calibrations with which said pointer is co-operable.

3. A structure of the class described comprising an instrument including a pair of legs one of which is adjustable toward and from the other, the intermediate portions of said legs being provided with opposed annular portions, a ring mounted for oscillation in one of said annular portions, an adjusting nut mounted for oscillation in the remaining annular portions, said adjusting nut being provided with a pointer, a feed screw connected with said nut intermediate its ends and swivelly connected at one end with said ring, said feed screw having its surface graduated for cooperation with said pointer.

4. A structure of the class described comprising an instrument embodying a pair of duplicate legs one of which is movable toward and from the other, an anchoring and swivelling ring mounted for oscillation on one of the legs, a nut mounted for oscillation on the remaining leg opposite said ring, said nut being provided with an indicating pointer, a hollow tubular feed screw formed at one end with a knurled finger grip, the opposite end being internally screw threaded, a screw cap connected with said last named end, said last named end being swivelly attached to said ring and the intermediate portion being attached to said nut, said feed screw being graduated for cooperation with said pointer.

5. A device of the class described, comprising a pair of legs one of which is adjustable toward and from the other, a feed nut carried by one of said legs, an adjusting screw operatively connected with said feed nut, a swivel connecting element between one end of said screw and the remaining leg, said feed screw being provided with graduations, and said nut being provided with a pointer cooperable with said graduations.
